US00D818466S

(12) **United States Design Patent** (10) Patent No.: **US D818,466 S**
Chang (45) Date of Patent: **** May 22, 2018**

(54) **PORTABLE ELECTRONIC DEVICE**

(71) Applicant: **GETAC TECHNOLOGY CORPORATION**, Hsinchu County (TW)

(72) Inventor: **Chia-Wei Chang**, Taipei (TW)

(73) Assignee: **Getac Technology Corporation**, Hsinchu County (TW)

(**) Term: **15 Years**

(21) Appl. No.: **29/611,915**

(22) Filed: **Jul. 26, 2017**

(51) LOC (11) Cl. **14-02**

(52) U.S. Cl.

USPC **D14/341**

(57) **CLAIM**

The ornamental design for a portable electronic device, as shown and described.

DESCRIPTION

FIG. 1 is a perspective view of a portable electronic device showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings depict portions of the portable electronic device that form no part of the claimed design.
